UNITED STATES PATENT OFFICE.

HERMAN F. D. CROWNFIELD, OF NEW YORK, ASSIGNOR TO M. H. BIRGE & SONS, OF BUFFALO, NEW YORK.

DESIGN FOR WALL-PAPER.

SPECIFICATION forming part of Design No. 23,649, dated September 25, 1894.

Application filed August 13, 1894. Serial No. 520,312. Term of patent 3½ years.

To all whom it may concern:

Be it known that I, HERMAN F. D. CROWNFIELD, a citizen of the United States, residing at New York, in the county and State of New York, have invented and produced a new and original Design for Wall-Paper, of which the following is a specification.

The design consists of a series of lyre-shaped ornaments with a lyre in the center of each of said ornaments, an open wreath of laurel leaves surrounding said ornaments and a bow of ribbon with flowing ends below said ornaments as represented in the accompanying drawing. The ornaments are placed at uniform distances apart over the surface of the paper.

The border or upper portion of the design

is formed of large hanging festoons of leaves and ribbons connected by upright ornaments and flowing ribbons. A rosette ornament is arranged in the center of said festoons, and from said rosette ornaments spring upright ornaments as shown in the drawing. A narrow ornamental band is arranged at the top and bottom of said border as shown.

What I claim is—

The design for wall paper herein shown and described.

Witness my hand this 8th day of August, 1894.

HERMAN F. D. CROWNFIELD.
